UNITED STATES PATENT OFFICE.

JOHN H. GOODFELLOW, OF LOWELL, MASSACHUSETTS.

AGITATING FIRE-GRAVE.

SPECIFICATION forming part of Letters Patent No. 535,984, dated March 19, 1895.

Application filed August 18, 1894. Serial No. 520,735. (No model.)

To all whom it may concern:

Be it known that I, JOHN H. GOODFELLOW, a citizen of the United States, residing at Lowell, Middlesex county, and State of Massachusetts, have invented certain new and useful Improvements in Agitating Fire-Grates, fully set forth in the following specification and illustrated in the accompanying drawings.

10 This invention relates to certain improvements in grates for stoves or furnaces and it has for its objects to provide a raking device for the same, which will not interfere with the dumping thereof; which will effectually 15 remove the ashes and loosen and distribute the fuel in the fire-box and to so construct the raking projections or fingers that they will not be liable to be burned out, as more fully hereinafter described. These objects 20 are attained by means illustrated in the accompanying drawings, in which—

Figure 1 represents a longitudinal vertical sectional view of a portion of a stove taken on the line $x-x$ of Fig. 1. Fig. 2, represents a 25 top plan view of the same with the fire-pot removed. Fig. 3, represents a transverse sectional view taken on the line $y-y$ of Fig. 1; Fig. 4, a perspective view of the raking device, detached; Fig. 5, a detached perspective view of one of the hangers by which the 30 raking device is suspended from the grate.

Referring to the drawings,—the numeral 1 indicates the walls of the stove, and 2, the fire-pot thereof, which, in the present instance, 35 is rectangular in form. The numeral 3 indicates a rectangular frame located below the fire-pot, within which the grate 4 is located, and which is provided with seats or bearings 5 for the journals or trunnions 6 at opposite 40 ends. The grate consists of a rectangular frame, having a series of longitudinal parallel grate-bars which extend above the upper edges of said frame. One of the trunnions projects through the wall of the stove and is 45 flattened or squared for the reception of a key or lever for dumping, as usual.

The upper surfaces of cross bars 20 are lower than the upper surfaces of the grate bars, so that the ends of the acute angular 50 projections at the base of the agitating heads may ride over the said cross-bars, and at the

same time be below the fuel, the said angular projections presenting to the fuel a wedge action, giving to it a rising and falling motion when the rake is reciprocated without at the 55 same time dragging the fuel along the grate surface, as would be the case if the fuel rested in the path of said angular projections.

The numeral 9 indicates the raking device. This consists of a rectangular frame, having 60 vertical rakes or fingers 10, which are arranged to set and travel in the spaces between the parallel grate-bars. The said grates are formed with triangular heads, the apices of which project above the grate-bars, while the 65 bases thereof set between the bars, for the purpose hereinafter explained. The raking-frame is half the length of the grate, and rests, normally, under one end of the grate.

The numeral 11 indicates a series of hangers, 70 which are provided with triangular heads, similar to the heads of the rakes or fingers 10, which project above the grate bars and act at the sides of the grate, similarly to the intermediate rakes or fingers 10. The heads of 75 these hangers are provided with lateral lugs 12, which set and ride upon the upper edges of the sides of the grate-frame. At their lower edges the hangers are provided with projections 13 which extend through and are 80 suitably fastened.

The rake-frame at its forward edge is provided with a socket 14, to receive one end of the operating-rod 15, which is recessed as indicated in Fig. 1 so as to engage the socket, 85 and permit the grate-frame to be reciprocated by said rod.

The numeral 16 indicates a lever which is fulcrumed to the lower edge of the front of the grate-frame, and which serves to lock the 90 grate against dumping at one side. The numeral 17 indicates a lug at the opposite side of the grate-frame, which holds the grate and prevents it from dumping at that side.

At the front of the stove on the inside, is 95 located a hinged scraper, which sets over the operating-rod 15 when the same is inserted in the stove, and serves to scrape any ashes that may collect upon the said rod when the same is withdrawn, and also to close the opening through which the rod is inserted when the same is not in use.

Below the grate-frame is located a frame 18 having flaring sides, which direct the ashes raked from the grate into the ash pan 19.

It will be observed that the transverse bar 20 of the grate-frame, forms an abutment to limit the rearward movement of the rake frame, the front bar forming an abutment to limit its forward movement.

At the front of the stove is formed an ash guard 21, which protects the opening through which the front journal of the grate passes and also the opening through which the operating-bar is inserted.

The operation of my invention is as follows: When it is necessary to rake the fire, the operating rod 15 is inserted through the opening at the front of the grate, and its recessed end is locked in the socket 14 by giving the rod a half turn. Then by reciprocating the rod the raking frame is moved back and forth, clearing the ashes from the grate and loosening and distributing the fuel thereon. To dump the grate the handle 15 is first removed and the lever 16 is moved so as to release the front edge thereof, and the grate-frame is turned down by means of a lever applied to its projecting journal as usual.

Having thus fully described my invention, what I claim, and desire to secure by Letters Patent, is—

1. The combination, in a stove with the grate thereof, of a rake-frame suspended below the same, by means of suitable hangers adapted to ride upon the upper side edges of the grate frame, and provided with fingers or rakes projecting upwardly between the grate-bars and a detachable operating-rod, whereby the said rake-frame may be reciprocated, substantially as specified.

2. The combination, with a stove grate, composed of parallel bars connected by cross bars, the upper surfaces of which are lower than the upper surfaces of the grate bars, of a rake frame provided with a series of vertical fingers, having triangular heads extending upward between the grate bars, with their apices above the upper surfaces thereof and the angular projections at their bases below the upper surfaces of said grate bars, and a series of hangers provided with lateral lugs adapted to set and ride upon the edges of the grate frame, and means for reciprocating the grate frame, substantially as specified.

In testimony whereof I have set my hand, this 6th day of August, 1894, in the presence of two subscribing witnesses.

JOHN H. GOODFELLOW.
